AMUSEMENT APPARATUS.

1,397,832.

Specification of Letters Patent.

Patented Nov. 22, 1921.

Application filed May 1, 1920. Serial No. 378,113.

To all whom it may concern:

Be it known that we, WALTER H. BALCKE and WILLIAM A. READY, citizens of the United States, residing, respectively, at

5 Winchester and Brighton, in the counties of Middlesex and Suffolk and State of Massachusetts, have invented new and useful Improvements in Amusement Apparatus, of which the following is a specification.

10 This invention relates to amusement apparatus of that class which comprises a phonograph and a dancing toy figure.

In devices of this character, it has heretofore been customary to drive the mechanism 15 which operates the dancing toy figure directly from the record disk centering pin by means of a clutch which engages the centering pin and is driven by frictional contact therewith. In many cases, however, the 20 centering pin does not project above the top of the record disk and in such cases, the clutch could not be connected to the centering pin and in any event a very accurate and close fit was necessary between the centering pin and the clutch, in order that the 25 centering pin should not slip in the clutch.

The object of the invention is to provide a mechanically operated toy figure and mechanism to operate the figure which is 30 driven by a member which has frictional contact with the record carrying disk or with the record disk supported on said record carrying disk, this member being driven entirely by frictional contact with one or the 35 other of said disks. To this end the member is made of heavy material, such as lead, and is preferably provided with three contact plugs, preferably made of rubber, whereby the driving member has a three 40 point contact with the record disk or with the record carrying disk, as the case may be.

The invention consists in the combination and arrangement of parts set forth in the following specification and particularly 45 pointed out in the claims.

Referring to the drawings:

Figure 1 is a front elevation of a phonograph having a mechanically operated toy or dancing toy figure embodying my invention connected therewith;

Fig. 2 is a plan view of the mechanism which imparts motion to the dancing toy figure and the casing in which it is inclosed;

Fig. 3 is an enlarged sectional elevation

taken on line 3—3 of Fig. 2 with the driving 55 member and a portion of the record carrying disk and record shown in connection therewith;

Fig. 4 is an underneath plan of the driving 60 member.

Like numerals refer to like parts throughout the several views of the drawings.

The invention as shown in the drawing is applied to a phonograph which may be of any usual or suitable construction and is 65 here shown as embodying a casing 10, a record disk carrier 12, a sound box arm 13 and a sound box 14; the handle 15 being provided for the purpose of winding the spring motor located within the casing 10 and 70 which rotates the record disk carrier 12. The casing 10 has embodied therein an amplifying horn 18, the opening of which is regulated by the doors 19.

The mechanically operated toy figure and 75 operating mechanism therefor includes essentially a platform and supporting means therefor adapted to be arranged on the phonograph casing and driving means for the toy figure arranged to be driven by 80 either the record disk carrier 12 or by a record disk 11, mounted on the record disk carrier 12.

20 represents the dancing platform which 85 is designed to be supported in elevated position above the record disk 11 and disposed radially relatively thereto and said platform has secured to it at one end arms 21 which extend downward and the extremities of said arms are secured to a weight 22 which rests 90 upon the phonograph casing outside the edge of the record disk carrier. The other end of said platform has a recess 23 in its underside into which the upper end 24 of a vertical rotary member 25 projects. 95

The rotary member 25 has a downwardly projecting extension 26 which is rotatably mounted in a bottom plate 27 of a casing 28. The casing 28 is provided with ears 29 and is fastened to the underside of the 100 platform 20 by tacks 30 which project through said ears and into said platform.

The extension 26 is provided with a slot 31 in its lower end and through said slot a pin 32 projects, said pin being fastened 105 at its opposite ends to a disk 33 constituting a driving member and preferably formed of lead or other heavy metal. The

driving member 33 has an annular groove 34 in its underside in which contact plugs 34' are fastened by means of pins 35. These contact plugs project below the disk 33 and 5 contact with either the record disk 11 or if there is no record disk, said contacts engage the record disk carrier 12. The record disk carrier 12 is provided with the usual disk centering pin 36 which is concentric 10 with the vertical rotary member 25. The driving member 33 is provided with a conical central orifice 37 into which the lower end of the extension 26 of the rotary member 25 projects. The lower end of said extension 15 is rounded off or made conical to engage the walls of the conical orifice 37.

The rotary member 25 is provided with a series of radially extending pins 40 which, during the rotation of said rotary member, 20 are adapted to alternately engage and release a cam lever 41. Said cam lever is formed of a plate of sheet metal and has a pair of oppositely disposed ears 42 on opposite edges thereof which are pivotally 25 mounted upon a shaft 43 extending across the casing 28. The end portion 44 of said cam lever is bent upwardly at 45 so that as the rotary member 25 is rotated in the direction of the arrow *a*, Fig. 2, the pins 40 30 alternately engage and release the raised portion 45 of the cam lever 41 and cause it to rock upon its pivotal shaft 43.

The rotary member 25 with the pins 40 thereof constitute a rotary cam. The end 35 46 of the cam lever 41 engages the lower end of a support 47 for the toy figures 48 and 49. The support 47 terminates at one end in a vertical shank 50 and at the other end in portions 51 which extend into the 40 figures 48 and 49 and between these two end portions 50 and 51 there is an intermediate portion 52 which is offset from the shank 50 and is bent to form a spring, the support being constructed of light spring 45 wire.

The figures 48 and 49 are formed with their arms and legs jointed to the back portion and when it rests, the feet of the figures just touch the upper surface of the platform 50 20.

In the drawings there are two dancing figures illustrated but it is evident that if desired one of these figures may be omitted and the other figure would perform the 55 dancing operation in the same manner as stated in relation to the two figures.

The operation of the device is as follows:

The driving member 33 is placed in position 60 upon the record disk 11 or upon the record disk carrier 12, as the case may be, with the orifice 37 approximately concentric with the centering pin 36. The platform 20 is then placed in position with the extension 26 projecting into the conical shaped

orifice 37 and with the cross pin 32 extending through the slot 31.

The figures are placed in position upon the platform 20 with the weight 22 resting upon the top of the casing 10 and with the shank 50 of the support 47 projecting downwardly through the tube 53 and resting upon the end 46 of the cam lever 41; said cam lever is provided with a rubber band 54 which deadens any noise that the cam lever 41 may otherwise make when dropping to its lowermost position and contacting with the bottom 27 of the casing 28.

When the phonograph is operated the record disk 11 or the record disk carrier 12, as the case may be, rotates the driving member 33 through frictional contact of the contact plugs 34' therewith and the pin 32 rotates the vertical rotary member 25 and the pins 40 on said vertical rotary member, thus causing the cam lever 41 to rock upwardly and downwardly and thus the support 47 is moved upwardly and downwardly and the dancing toy figures attached thereto are alternately moved into and out of contact with the platform 20. At the same time the shank 50 of the support 47 is adapted to rotate in the tube 53 and said figures therefore have given to them an upward and downward movement and a rotary movement while at the same time their arms and legs being jointed to the body portions thereof assume different amusing positions and give the figures all the semblance of dancing.

It has been found by operating the device hereinbefore described if the driving member 33 is placed upon the record disk or upon the record disk carrier, eccentric to either one of said disks, and a rotary motion imparted to the rotary disk that said driving member will automatically position itself concentrically with relation to the disk and also with relation to the vertical rotary member 25, thus making it unnecessary for the driving member to be accurately positioned by the operator concentric with the disk and with the vertical rotary member 25.

While we have described our invention as particularly adapted to imparting movement to a toy figure from a phonograph disk, it is evident that the combination of a horizontal rotary member, a vertical rotary member and a driving member positioned upon the horizontal rotary member and having frictional contact therewith and being connected to the vertical rotary member, whereby upon rotating the horizontal rotary member the vertical rotary member will be rotated, might be used for other purposes than the specific purpose of imparting movement to a dancing toy and we do not wish to be understood as limiting our invention to such specific use.

It will be understood that the device of

this invention is operative when the driving member 33 is placed upon the record disk or on the record carrying disk and, therefore, in the claims the word disk may be 5 understood as applying either to the record disk 11 or to the record disk carrier 12.

We claim:

1. In combination a horizontal rotary member, a platform located thereabove, a 10 dancing figure positioned above said platform, a vertical reciprocating member upon which said figure is mounted, mechanism adapted to reciprocate said reciprocating member, a driving member for said mechanism supported upon said horizontal rotary member and frictional means interposed between said driving member and said horizontal rotary member, whereby said driving member may be frictionally driven, while 15 stationary relatively to said horizontal rotary member.

2. In combination, a rotary disk, a dancing figure, mechanism adapted to impart motion to said figure, a driving member for 25 said mechanism mounted upon said rotary disk and frictional means interposed between said rotary disk and driving member whereby said driving member may be frictionally driven while said driving member 30 is stationary relatively to said rotary disk.

3. In combination, a rotary disk, a stationary platform, a dancing figure positioned above said platform, mechanism adapted to impart motion to said figure, a driving member for said mechanism mounted upon said rotary disk and frictional means fast to said driving member and projecting downwardly therefrom into contact with said rotary disk, whereby said mechanism may be driven by 35 40 said driving member while said driving member is stationary relatively to said rotary disk.

4. In combination, a rotary disk, a stationary platform, a dancing figure positioned 45 above said platform, mechanism supported upon said platform adapted to impart motion to said figure, a driving member for said mechanism mounted upon said rotary disk and yielding frictional means interposed between said rotary disk and driving member, whereby said mechanism may be driven by said driving member while said driving member is stationary relatively to 50 said rotary disk.

5. In combination, a casing, a rotary disk, a platform mounted on said casing and projecting over said disk, a dancing figure positioned over said platform, mechanism adapted to impart motion to said figure, a driving member for said mechanism mounted upon said rotary disk and rubber frictional means interposed between said rotary disk and driving member, whereby said mechanism may be driven by said driving 55 60 member.

member while said driving member is stationary relatively to said rotary disk. 65

6. In combination, a horizontal rotary disk, a driving member supported upon said disk, a plurality of frictional contact plugs on the lower face of said driving member 70 and contacting with said horizontal rotary disk, a platform movably positioned upon a stationary support and projecting over said disk and mechanism including a vertical rotary member mounted on said platform and engaging said driving member whereby said vertical rotary member may be rotated by said driving member through frictional contact of said plugs with said disk while stationary relatively thereto. 75 80

7. In combination, a horizontal rotary disk, a driving member supported upon said disk, yielding frictional means fast to said driving member upon its lower face and projecting downwardly therefrom into contact 85 with said rotary disk, a platform movably positioned upon a stationary support and projecting over said disk and mechanism including a vertical rotary member mounted on said platform and engaging said driving member, whereby said vertical rotary member may be rotated by said driving member through frictional contact of said yielding frictional means with said disk and said driving member may be concentrically 90 95 positioned upon said disk.

8. In combination, a horizontal rotary disk, a vertical rotary member, a bearing for said vertical rotary member movably mounted upon a stationary support, a driving member positioned upon said disk, a plurality of rubber plugs fast to said driving member and projecting downwardly therefrom into contact with said horizontal rotary disk, said driving member being connected to said vertical rotary member, whereby upon rotating said disk said driving member will be automatically concentrically positioned upon said disk and said vertical rotary member will be rotated. 100 105 110

9. In combination, a casing, a disk rotatably mounted upon said casing, a platform supported upon said casing and movable relatively thereto, a dancing figure supported above said platform, mechanism supported upon said platform adapted to impart motion to said figure, a driving member mounted upon said rotary disk and frictional means upon the lower face of said driving member adapted to engage said rotary disk, whereby said mechanism may be driven by said driving member through frictional contact with said disk while said driving member is stationary relatively thereto. 115 120

10. In combination, a casing, a disk rotatably mounted on said casing, a support movably mounted upon said casing, a vertical rotary member mounted upon said sup-

port and having a slot extending transversely thereof, a driving member positioned upon said disk, yielding frictional means fast to said driving member and projecting 5 downwardly therefrom into contact with said rotary disk and a pin on said driving member extending through said slot whereby upon rotating said disk said driving member will be automatically concentrically 10 positioned upon said disk and said vertical rotary member will be rotated.

11. In combination, a horizontal rotary member, a vertical rotary member, a bearing for said vertical rotary member, a driving member positioned upon said horizontal rotary member and frictional means interposed between said driving member and horizontal rotary member, said driving member being connected to said vertical rotary member whereby upon rotating said horizontal rotary member a rotary motion 15 will be imparted to said vertical rotary member through said driving member, while said driving member is stationary relatively to said horizontal rotary member.

12. In combination, a horizontal rotary member, a vertical rotary member, a bearing for said vertical rotary member movably mounted upon a stationary support, a driving member positioned upon said horizontal rotary member, a plurality of rubber plugs spaced apart, fast to said driving member and projecting downwardly therefrom into contact with said horizontal rotary member, 30 said driving member being connected to said vertical rotary member, whereby upon ro-

tating said horizontal rotary member said driving member will be automatically concentrically positioned upon the said horizontal rotary member and said vertical rotary member will be rotated while said driving member is stationary relatively to said horizontal rotary member. 40

13. In combination, a rotary disk, a dancing figure, means adapted to impart motion 45 to said dancing figure, a driving member mounted upon said rotary disk and yielding frictional means interposed between the lower face of said driving member and said rotary disk and contacting with said rotary 50 disk, whereby said means may be operated to impart motion to said dancing figure while said driving member is stationary relatively to said rotary disk.

14. In combination, a rotary disk, a dancing figure, means adapted to impart motion 55 to said dancing figure and a driving member mounted upon said rotary disk with a plurality of frictional contact plugs on its lower face contacting with said rotary disk 60 and adapted to operate said means to impart motion to said dancing figure while said driving member is stationary relatively to said rotary disk.

In testimony whereof we have hereunto 65 set our hands in presence of two subscribing witnesses.
